MAPEARL CURTIS BEE, OF NEW YORK, N. Y.

COMBINATION UNDERGARMENT FOR WOMEN'S WEAR.

Application filed May 12, 1924. Serial No. 712,500.

To all whom it may concern:

Be it known that I, MAPEARL CURTIS BEE, a citizen of the United States, and a resident of the city, county, and State of New York, have invented an Improvement in Combination Undergarments for Women's Wear, of which the following is a specification.

This invention relates to undergarments and particularly to union or combination undergarments for women's wear.

A single embodiment of the invention is shown in the accompanying drawings, wherein—

15 Figure 1 is a front elevation, and

Figure 2 is a vertical section taken on the line 2—2 of Figure 1.

Various efforts have been made to combine undergarments satisfactorily, but these 20 combinations have invariably resulted in garments of unusual and undesirable shape and appearance, wherein proper fit, hang and lines have necessarily been sacrificed to the mechanical requirements of construction.

In accordance with the present invention, however, the combination of such usual garments as the brassière and the chemise, or similar article of underwear, is effected not 25 only without sacrifice of proper hang and fit, but in such a manner that economy in manufacture, simplicity and convenience in use, and convention in shape, are at the same time obtained.

30 As shown in the drawings, the garment illustrated is a chemise 3 of the so-called envelope type, combined with a brassière 4. To form the brassière, the fabric of the chemise is shown extended and folded in at the top, thus producing a combination

chemise and brassière in one piece—and yet as effectively separate from each other when worn as would be the case were they not so joined.

By thus having, in effect, a brassière and 45 chemise which are joined to each other at their top edges, it results that the garments, when worn, assume and remain in their proper and usual position. The brassière portion, provided with elastic inserts 5, is 50 adapted to fit snugly about the wearer and to afford the required support—while the chemise portion hangs freely from its top edge, as is desirable to promote comfort and the proper fit of outside or other clothing. 55

Single shoulder straps or ribbons 6, or other usual supporting means, are sufficient to support both portions or units of the combination garment, which, while effectively 60 constituting an economical combination of two or more garments, preserves the proper fit, comfort and appearance of each. A suitable tab or tape to be fastened to a corset may be secured to the lower edge of the brassière and depend therefrom as 65 shown.

Claim:

A union garment comprising a chemise and a brassière, the fabric of the chemise being extended at the top and folded inwardly and downwardly to form the brassière, the brassière having at its lower edge an elastic insert adapted to fit snugly about the wearer to afford support, together with shoulder straps secured to the brassière and 70 chemise at the fold of the material. 75

In testimony whereof, I have signed my name to this specification this 5th day of May, 1924.

MAPEARL CURTIS BEE.
